DROP WIRE

Application filed July 9, 1930. Serial No. 466,706.

This invention is a continuation in part of my co-pending application Ser. No. 350,401 and is concerned more particularly with the drop wire used in the electrical warp stop motion shown in said application.

The warp stop motion to which my invention relates has a contact bar extending through slots in their upper portions of the drop wires. The bar is formed of two electrodes one of which is grounded and acts as an inclosing support for the live electrode insulated therefrom. I find it convenient to locate the exposed surface of the live electrode within the outline of the grounded electrode, this construction requiring a lateral motion on the part of the drop wire to establish electrical connection between the electrodes. This lateral motion is brought about by the coaction of a lobe on the drop wire extending into the slot and positioned to engage a longitudinally extending camming rib on the grounded electrode. As the drop wire falls the lobe is moved laterally by the rib and the drop wire must be provided with clearance above the lobe to permit the lateral motion.

In drop wires having slots of any appreciable width in their upper portions there is the chance that one drop wire will move into the slot of an adjacent wire and support the latter even though its warp be defective. The harnessing of the warp requires that certain threads and their drop wires be raised while others are depressed. At the beat-up of the lay all of the threads are subjected to a temporary increased tension which may result in a slight upward movement of the drop wires, some of them moving farther than others. In each of these instances a condition exists which permits drop wires to become interlocked. Also, at the time of warp fault the drop wire of the defective thread will be down on the bar, but will be raised when the weaver corrects the fault, and this raising might cause interlocking.

Various attempts have been made to form drop wires either with rounded tops or with extended upper ends in order to prevent the interlocking. The drop wire must always be so proportioned that the major part of its

weight lies below the surface which rests on the warp in order to retain the drop wire in upright position, and this consideration limits the height of the solid part of the drop wire above the slot. It is an important object of my present invention to place the previously mentioned lobes in such a position that when a drop wire is in the lowest position it can occupy the upper end thereof will be in alignment horizontally with the lobe of an adjacent elevated drop wire. In this way I prevent a low drop wire from having an upper corner thereof pass into the slot of the adjacent drop wire.

With the objects indicated above and others which will appear as the description proceeds, my invention resides in the combination and arrangement of parts hereinafter described and set forth in the claim.

In the accompanying drawing, wherein a convenient embodiment of my invention is set forth,

Fig. 1 is a vertical central section through a warp stop motion employing my improved bar and drop wire,

Fig. 2 is a section similar to a portion of Fig. 1 showing the relation between the contact bar and two drop wires one of which is indicated raised in full lines and the other down in dotted lines.

As shown in Fig. 1 a threaded supporting rod R has strung therealong a plurality of supporting and spacing units 10 the right hand one of which may be engaged by a nut 11 on the rod effective to clamp said units against an end plate 12 movement to the left of which is resisted by nut 13 on the rod. Each contact bar, designated generally at B, has an outer inclosing sheath or grounded electrode 14 having a vertical wall 15 in which is formed a longitudinally extending rib 16. The top and bottom edges of the grounded electrode are bent horizontally and then downwardly and upwardly, respectively, as at 17 and 18, to define grooves between which are located the upper and lower ends of a live electrode 19. The latter has a contact surface 20 which lies within the outline of the grounded electrode, that is, a line joining the right hand surfaces of the

bent ends 17 and 18 as shown in Fig. 2 will pass to the right of the surface 20. Suitable insulating material may be provided to maintain the electrodes in electrical separation.

- 5 The matter already described is substantially the same as that set forth in my aforesaid application and so far as this invention is concerned it is significant to note that the top folded over edge 17 of the grounded electrode projects beyond the live surface 20, so that access to the latter by a body falling past said grounded edge 17 is afforded only by a lateral motion to the left as viewed in Fig. 2 on the part of the falling body.
- 10 15 The drop wire D forming the subject matter of my present invention has an open slot 30 in the bottom portion thereof to receive a warp thread and has a closed slot 31 in the upper part thereof, there being a hole 32 punched between said slots for the purpose of reducing the weight of the drop wire. The slot 31 has lower and upper portions 33 and 34, respectively, which are separated by lobes or similar inwardly extending camming projections 35. The right and left hand edges of the lower part of the slot may be defined by walls 36 and 37, respectively, while the corresponding walls of the upper part 34 may be defined by walls 38 and 39, respectively.
- 20 25 30 35 30 The walls 37 and 39 are in alignment, though not necessarily so, and this relation is also true of the walls 36 and 38. It is important to note, however, that the space between the upper walls 38 and 39 is greater than the distance separating nearest parts of the right and left hand lobes 35 as designated by points 40 and 41, respectively.

In operation, the warp W will normally support the drop wire so that the lobes are above the top edge of the bar, thereby keeping the surface 20 electrically separated from the grounded electrode. When a drop wire falls the lobe having point 41, for instance, will engage the rib 16 to move the drop wire to the left, the corresponding point 40 of the other lobe having previously fallen to a point below the rounded edge 17 of the inclosing electrode. The right hand lobe will therefore move under the upper right hand edge of the bar, and the wall 38 will approach the bar. This necessary lateral movement of the wire is possible because the upper part 34 of the slot is of sufficient width. Current may then flow from the live electrode through the right hand lobe, through the drop wire, through the opposite lobe and rib 16, to the grounded electrode.

40 45 50 55 60 The drop wire is preferably symmetrical about its vertical central axis so that it may be threaded or strung on the bar with either the wall 36 or the wall 37 to the right, and the points 40 and 41 are preferably in horizontal alignment when the drop wire is upright. As shown herein the lobes are symmet-

rical about a horizontal axis passing through them, but this is not a necessary relation.

From an inspection of Fig. 2 it will be seen that when a drop wire, such as the one indicated in dotted lines, is in the lowest position 70 which it can occupy because of the engagement with the detector bar, the top edge 50 thereof will lie opposite portions of the lobes 35 and the laterally offset position of the detector which might otherwise permit it to 75 become interlocked with the adjacent drop wire shown raised in full lines, is prevented by said lobes. As the weaver ties a broken warp there is therefore no likelihood that the corresponding drop wire will become entangled with either of the drop wires adjacent thereto as it is raised.

80 85 90 95 From the foregoing it will be seen that I have provided a drop wire for an electrical warp stop motion so proportioned that it may have the necessary lateral movement to electrically connect the insulated electrodes of the bar. It will also be seen that the lobes which act to effect a lateral movement of one drop wire will in another drop wire occupy a higher position and serve to prevent interlocking of the drop wires.

Having thus described my invention it will be seen that changes and modifications may be made therein by those skilled in the art 95 without departing from the spirit and scope of the invention and I do not wish to be limited to the details herein disclosed, but what I claim is:

100 A drop wire for an electrical warp stop motion having a contact bar, said drop wire having a closed slot formed in its upper end portion and having a pair of substantially opposite circuit-closing lobes projecting into said slot from each side thereof and intermediate the ends thereof, the lower edge portions of both lobes being upwardly and inwardly inclined to facilitate a circuit-closing movement, and the adjacent edges of said lobes being substantially separated to permit 105 portions of said contact bar to pass upward between said lobes before a circuit is closed thereby.

110 In testimony whereof I have hereunto affixed my signature.

OSCAR V. PAYNE.
